(57) **CLAIM**

We claim the ornamental design for a baseball helmet window cling, as shown and described.

DESCRIPTION

FIG. 1 is a perspective view of a baseball helmet window cling, showing our new design;

FIG. 2 is a front elevational view thereof;

FIG. 3 is a rear elevational view thereof;

FIG. 4 is a left-side elevational view thereof, the right-side elevational view being a mirror image thereof; and,

FIG. 5 is a top plan view thereof, the bottom plan view being a mirror image thereof.

The broken lines showing a window in FIG. 1 and a logo and text in FIGS. 1-3 depict environmental matter and form no part of the claimed design.
